UNITED STATES PATENT OFFICE.

CHARLES O. STANLEY, OF BUFFALO, NEW YORK, ASSIGNOR OF FIFTY-FIVE PER CENT.
TO GEORGE A. STRICKER, OF BUFFALO, NEW YORK.

TORPEDO-HOLDER.

1,330,823.

Specification of Letters Patent. Patented Feb. 17, 1920.

Application filed May 24, 1919. Serial No. 299,601.

To all whom it may concern:

Be it known that I, CHARLES O. STANLEY, a citizen of the United States, residing at Buffalo, in the county of Erie and State of New York, have invented new and useful Improvements in Torpedo-Holders, of which the following is a specification.

This invention relates to an improved torpedo holder whereby torpedoes are held on a rail of a railway track, so that when the wheels of a locomotive or car run over the same, a detonation will be produced which will serve as a signal for the trainmen.

It is the purpose of this invention to produce a holder of this character which is very simple and inexpensive in construction, capable of being quickly and easily applied to the rail and which will permit the wheels of a locomotive or car to run over the same and discharge the torpedo with certainty and without liability of the torpedo holder being displaced from its operative position when these wheels run over the same in either direction of the rail.

In the accompanying drawings: Figure 1 is a perspective view of the preferred form of my improved torpedo holder applied to a section of a rail. Fig. 2 is a vertical transverse section of the same, on an enlarged scale.

Similar characters of reference indicate corresponding parts in both views.

The form of rail to which my improved torpedo holder is particularly applicable comprises a horizontal base 3, a longitudinal stem or web 4 rising from the central part of this base, and an enlarged head 5 arranged at the upper end of the stem.

My improved torpedo holder comprises a longitudinal presser or running bar 6 which is preferably constructed of a strip of resilient material, such as sheet steel, and is bent or curved in substantially bow-form so that its central part is higher than its opposite ends 7, 7. The latter are preferably beveled so that upon placing this presser bar on top of a rail its ends will engage with the top of the rail and form joints therewith which lead over gradually from the top of the rail to the upper side of the presser bar and thus avoid the formation of any abrupt shoulders or obstructions between these parts, as shown in Fig. 1.

8 represents a cross piece which is also

preferably constructed of sheet metal and secured with its central part to the underside of the central part of the presser bar by means of rivets 10, 10, as shown in Figs. 1 and 2, or by any other suitable means. 60 One end of this cross piece is provided with a downwardly and inwardly-projecting hook 9 which is adapted to engage underneath the head of the rail on one side thereof, thereby retaining the holder against upward movement and also against lateral motion with reference to the rail. The opposite end of the cross piece is provided with a downwardly-projecting arm 11 which is arranged along the opposite side of the head 70 of the rail,—the lower end of this arm being provided with an upwardly projecting finger 12 which is formed by reversely bending the lower part of this arm. The cross piece, together with its hook, arm and 75 finger, is preferably constructed from a single piece of metal. The lower part of the arm and the adjacent part of the finger are provided with coinciding screw threaded openings 13, 14. These screw threaded 80 openings receive the externally screw threaded shank 15 of a clamping screw which is adapted to engage its inner end with the stem or web of the rail underneath the head thereof opposite that side which is engaged 85 by the hook 9. The outer end of this clamping screw is provided with a finger piece or head 16 for permitting the same to be turned by hand although this may be accomplished in any other suitable manner. 90

Underneath the central parts of the cross piece and the presser bar is arranged a retaining cap or cup 17 which is preferably constructed of sheet metal and secured to these parts of the cross piece and the presser 95 bar by the same rivets 10 which connect the presser bar and cross piece. Between the cavity on the underside of this cap and the top of the rail is arranged the torpedo 18 which is to be retained on the rail and to 100 be exploded by the pressure of the locomotive or car wheels running over the same and thus serves as a signal for the operatives to be on their guard. By means of the annular flange of this cap which embraces the 105 torpedo, the latter is reliably retained in position on the top of the rail head, so that the torpedo is not liable to be shaken off from the rail due to vibration as the locomotive or cars approach the torpedo holder from 110

either direction, thereby insuring giving a signal to the trainmen.

Owing to the fact that the opposite ends of the presser bar hug or fit the top of the rail head very closely, so that practically a flush joint is produced between the same, it is possible for the wheels of the locomotive or cars to run onto the presser bar and explode the torpedo without any danger of 10 the torpedo holder being brushed off of the rail or becoming displaced thereon lengthwise, which otherwise might result in failure to give a warning signal to the trainmen.

15 By constructing the presser bar and cross piece of two separate pieces of metal which are connected in the manner shown, it is possible to produce this torpedo holder at comparatively low cost. The means for attaching 20 this holder are also very simple and inexpensive and permit of accomplishing this quickly and easily. Furthermore, by engaging the clamping screw with the corresponding threaded openings formed in the arm and the reversely bent finger of the cross piece, an effective screw connection is obtained 25 between the cross piece and the clamping screw without the use of a separate screw nut for this purpose. The resilience of the finger 12 relative to the arm 11 also serves to hold the clamping screw securely against turning, so that the torpedo holder when applied to a rail will not be liable to be displaced by vibrations of the track, thereby 30 insuring proper retention of the torpedo holder on the rail and warning the trainmen at the proper time.

I claim as my invention:

1. A railway torpedo holder comprising a 40 longitudinal upwardly curved presser bar which in its operative position is adapted to rest at its opposite ends on the upper side of the rail while its central part is elevated above the same and extends over a torpedo placed on the rail, and means for attaching 45 said presser bar to the rail.

2. A railway torpedo holder comprising a longitudinal upwardly curved presser bar which in its operative position is adapted to 50 rest at its opposite ends on the upper side of the rail while its central part is elevated above the same and extends over a torpedo placed on the rail, means for attaching said presser bar to the rail comprising a cross piece secured with its central part to the central part of said presser bar and provided at one end with a downwardly and inwardly projecting hook which is adapted to engage underneath

the rail head on one side thereof, and a clamping screw mounted on the other end 60 of said cross piece and adapted to engage the rail underneath its head on the opposite side thereof.

3. A railway torpedo holder comprising a longitudinal upwardly curved presser bar 65 which in its operative position is adapted to rest at its opposite ends on the upper side of the rail while its central part is elevated above the same and extends over a torpedo placed on the rail, means for attaching said presser bar to the rail comprising a cross piece secured with its central part to the central part of said presser bar and provided at one end with a downwardly and inwardly projecting hook which is adapted to engage 70 underneath the rail head on one side thereof and provided at its opposite end with a downwardly projecting arm which has its extremity bent reversely in the form of a finger, said arm and finger being provided 75 with coinciding screw threaded openings, and a clamping screw engaging said threaded openings and adapted to engage the rail underneath its head on the opposite side thereof. 80

4. A railway torpedo holder comprising a longitudinal upwardly curved presser bar which in its operative position is adapted to rest at its opposite ends on the upper side 90 of the rail while its central part is elevated above the same and extends over a torpedo placed on the rail, means for attaching said presser bar to the rail, and a cap connected with the underside of said presser bar and adapted to receive a torpedo. 95

5. A railway torpedo holder comprising a longitudinal upwardly curved presser bar which in its operative position is adapted to rest at its opposite ends on the upper side of the rail while its central part is elevated 100 above the same and extends over a torpedo placed on the rail, means for attaching said presser bar to the rail comprising a cross piece secured with its central part to the central part of said presser bar and provided at one end with a downwardly and inwardly projecting hook which is adapted to engage underneath the rail head on one side thereof, a clamping screw mounted on the other end 105 of said cross piece and adapted to engage the rail underneath its head on the opposite side thereof, and a cap secured to the underside of the central parts of said presser bar and cross piece and adapted to receive a torpedo. 110

CHARLES O. STANLEY.
